UNITED STATES PATENT OFFICE.

JOSEPH F. MORIN, OF LAWRENCE, MASSACHUSETTS.

BARREL-COVER.

SPECIFICATION forming part of Letters Patent No. 678,675, dated July 16, 1901.

Application filed March 26, 1901. Serial No. 52,918. (No model.)

To all whom it may concern:

Be it known that I, JOSEPH F. MORIN, of Lawrence, in the county of Essex and State of Massachusetts, have invented certain new 5 and useful Improvements in Barrel-Covers, of which the following is a specification.

This invention has for its object to provide a barrel-cover which shall permit a ready inspection of the contents of the barrel or a 10 sample thereof and shall prevent unauthorized removal of the said contents or sample, the invention being intended particularly for the use of grocers and others who desire to expose samples of their produce for sale.

15 The invention consists in the improvements which I will now proceed to describe and claim.

Of the accompanying drawings, forming a part of this specification, Figure 1 represents 20 a side view of a barrel-cover embodying my invention, a part of the supporting-flange being broken away. Fig. 2 represents a view similar to Fig. 1, showing the opposite side of the cover. Fig. 3 represents a section on 25 line 3 3 of Fig. 1, showing in dotted lines a portion of a barrel to which the cover is applied.

The same reference characters indicate the same parts in all the figures.

30 In the drawings, *a* represents a cylindrical band, which constitutes the wall of a circular tray or receptacle and is hereinafter referred to as the "outer" band. The upper edge of the outer band *a* is provided with an inwardly-projecting lip *a'*, preferably formed by rolling the sheet metal of which the band is composed over a wire core *a²*, as shown in Fig. 3.

b represents an inner band, which bears against the inner surface of the outer band *a* 40 and has at its upper edge an inwardly-projecting lip *b'*, which is separated from the lip *a'* of the outer band by a space of sufficient width to receive the margin of a circular pane *c* of glass, which forms the transparent cover 45 of the tray, of which the bands *a* and *b* constitute the circular wall. The inner band *b* is detachable from the outer band, so that it can be removed in case it becomes necessary to replace a broken pane *c* with a new one, 50 the inner band being here shown as secured to the outer band by means of a bolt *d*, passing through the two bands, and a nut *d'*,

screwed upon the bolt. The band *b* is preferably made of a strip of sheet metal, the ends of which are overlapped at the point 55 where the bands are secured by the bolt *d*, so that when the bolt is removed the band *b* may be contracted and readily removed from the outer band *a*. In this embodiment of my invention the outer band is provided at its 60 lower edge with an inwardly-projecting lip *a³*, which supports the lower edge of the inner band *b*, so that a single bolt *d* is sufficient for the confinement of the inner band.

e represents a circular bottom piece, which 65 is connected by a hinge *f* with the outer band *a* and is adapted to swing downwardly from the body of the receptacle. The swinging edge of the bottom piece is provided with a catch member, here shown as a resilient 70 sheet-metal ear *g*, attached to the bottom piece and bent upwardly around the edge of the same, its upwardly-bent portion having a slot *g'*, adapted to engage an ear *g²*, affixed to the outer band *a*. 75

To the outer band *a* is affixed an outwardly-projecting flange *i*, which is adapted to rest upon the upper end of a barrel *j* and has a downwardly-projecting portion or rim *i'*, which surrounds the upper end of the barrel, 80 as indicated in Fig. 3. The downwardly-projecting portion *i'* of the flange may be connected with the barrel by a hinge *k*, as shown in dotted lines in Fig. 3, or, if preferred, the hinge *k* may be omitted, the flange being entirely separable from the barrel. 85

When it is desired to fill the sample-tray above described, the tray is inverted, so that the glass pane *c* forms its bottom, the bottom piece *e* is opened, and the sample is inserted, 90 after which the bottom piece is closed and the tray is applied to the barrel in the position shown.

It will be seen that the described device constitutes a simple and effectual device for 95 closing or covering the mouth of a barrel and at the same time displaying a sample of its contents.

I claim—

A barrel-cover comprising a cylindrical 100 outer band having an inwardly-projecting lip at its upper edge, a cylindrical inner band detachably secured to the outer band within the latter and having an inwardly-projecting

lip at its upper edge, a circular pane of glass confined at its margin between the lips of the inner and outer bands, a circular bottom piece hinged to the lower edge of the outer band, fastening members secured respectively to the said bottom piece and the outer band, and a supporting-flange extending outwardly from the upper portion of the outer band to rest on the upper end of a barrel, and

extending downwardly to inclose said upper end.

In testimony whereof I have affixed my signature in presence of two witnesses.

JOSEPH F. MORIN.
